UNITED STATES PATENT OFFICE

FRANK E. JOHNSON, OF NEW BEDFORD, MASSACHUSETTS, ASSIGNOR TO JOHN I. PAULDING, INC., OF NEW BEDFORD, MASSACHUSETTS, A CORPORATION OF MASSACHUSETTS

SWITCH FOR ELECTRIC LAMPS

Application filed August 24, 1928. Serial No. 301,715.

This invention relates to switches for electric lamps and is exemplified in a switch adapted to be operated by a push button.

The principal object of the invention is the provision of an efficient and durable switch of improved and economical construction.

Another object of the invention is to insure a more perfect electrical contact when the switch is closed.

A further object of the invention is the provision of simple means for mounting the push through switch member to prevent looseness after long wear.

An additional object is to provide a construction in which the various parts may be made from ribbon material thereby reducing the cost of construction.

Other objects of the invention will be more specifically pointed out and described hereinafter.

In its preferred embodiment my invention contemplates a switch comprising a pivotally mounted movable member adapted for closing or opening the lamp circuit when thrown into or out of engagement with a fixed contact. The movable member is moved from one position to the other by a spring under compression having one end bearing on said member and the other end connected to a push-button member in an off center relation to said movable member. The operation of the push button member moves its end of the spring from one side of the movable member to the other side thereof thereby throwing the movable member in a direction reverse to the movement to the end of the spring. In the illustrative embodiment of the invention hereinafter described, a push-through member is mounted for longitudinal reciprocation to throw the spring in one direction or the other for operating the movable member to close or open the lamp circuit.

One of the important features of my invention resides in a construction in which the closing of the switch effects a sliding contact between flat surfaces over a relatively large area in distinction to a contact between edges with the result that the electrical con-

tact is far more efficient and complete and arcing is diminished.

Another important feature of the invention relates to the method of mounting the push-through switch member which actuates the switch. Preferably this member is carried by a U-shaped yoke support having in its two upright members open L-shaped recesses and the push-through member is made in the form of a flat bar having end push-buttons mounted thereon. This construction permits the push-button bar to be mounted in the yoke through the open ends of the recesses and then turned to rest on the bottom of the recesses and is held in that position by the overhanging parts of the two upright ends of the yoke and by the actuating spring for the movable member. As a result of this construction, the push-through slide member will never work loose irrespective of the length of use to which the switch is subjected and yet it can be very easily removed from the yoke member when necessary.

Another important feature of my invention resides in economy of construction. All the parts of the switch except the fixed contact may be stamped out of ribbon material and are what is known as one-operation parts. The contact is a two-operation part requiring first, stamping out of thin sheet material and second, bending. This conduces to economy of construction and enables the switch to be made at a very low cost.

In the drawings illustrating one embodiment of the invention, Figure 1 is a side elevation on an enlarged scale of an electric lamp socket having a switch constructed and adapted to be operated in accordance with my invention, the shell of the socket being partially cut away to expose the switch mechanism which is shown in open position; Fig. 2 is a vertical central sectional view also on an enlarged scale on line 2-2 in Fig. 1 looking from right to left but with the switch closed; Fig. 3 is a plan view of the socket on a reduced scale looking downwardly in Fig. 1; Fig. 4 is a cross-sectional view also on a reduced scale on line 4-4 in Fig. 1 looking downwardly; Fig. 5 is a bottom plan view on the same scale; Fig. 6 is a side elevation partly in sec-

tion of the switch mechanism; Fig. 7 is an end elevation of the switch frame; Fig. 8 is a view in perspective of the contact; Fig. 9 is a side elevation of the switch frame; Fig. 10 is a side elevation of one form of standard and Fig. 11 is a view in perspective of the pivot plate.

Referring to the drawings showing an electric lamp socket containing one embodiment of the invention by way of illustration, 10 indicates an upper insulating block of porcelain, fibre or other suitable molded material and 12 a lower insulating block of similar material, the two blocks being connected together in separated relation by two U-shaped standards 14 and 16 at opposite sides. The standard 14 is fastened to the blocks 10 and 12 by screws 18 and 20 respectively and the standard 16 to the same blocks by screws 22 and 24 respectively, the blocks being recessed to receive the ends 20 of the standards. The screws 20 and 24 also serve to fasten the threaded lamp socket 26 of usual form to the outer face of the block 12.

The standards 14 and 16 are provided with binding screws 28 and 30 respectively for holding the ends of conductors 32 and 34 respectively and the upper block is suitably recessed at 36 and 38 to permit the conductors to be led out. To secure compactness and to facilitate attachment of the wires, the binding screw portions of the standards are offset and are bent inwardly to form in each case a seat for the binding screw with adjacent shoulders to hold the wires under the binding screw and against detachment therefrom.

35 The switch for controlling the lamp circuit comprises a movable contact 40 in the form of a breaker bar adapted to be thrown into and out of engagement with a fixed contact 41 by the operation of a spring 42, 40 through the manipulation of a push-through member 43. The fixed contact 41 is connected by a neck 44 to a butt 45 provided with a central hole 46 whereby it may be mounted on the screw 18 and secured in position between the upper end of the standard 14 and the inner face of the block 10. When thus fastened the contact 41 is in a position between the two standards to be engaged by the breaker bar 40. The latter is U-shaped 50 and is pivotally mounted at its two bored ends on two ears 48 on a pivot plate 49 set in a central square recess formed in the U-shaped yoke which in turn sets on the inner face of the block 12. The ears are first turned upwardly from the plate and then outwardly to pivot the breaker bar above the plate. A rivet 50 through the block 12 holds the pivot plate in position and also holds a central contact 51 on the outer face of said block in position to be engaged by the butt end of the lamp inserted in the socket 26, said contact 51 being insulated from the said socket by a surrounding ridge 52 formed on the outer face of the block 12.

65 For supporting the push-through mem-

ber 43, a rectangular frame 54, substantially U-shaped in form, is set in a rectangular recess in the inner face of the lower block 12 with its two ends projecting upwardly and having each an L-shaped open recess 55, which permits the member 43 to be inserted edgewise therein and then turned to lie on the bottom edges 56 of the recesses. The overhanging portions 57 lock the push-through member in place but do not prevent it being withdrawn from the frame when necessary. The push-through member 43 is preferably in the form of a flat bar having its two ends bent into an offset relation to the main body thereof and provided with push buttons 58 and 59, the former of which may be colored red to denote the end to be pushed in to close the circuit and light the lamp and the latter colored black for opening the circuit.

The frame 54 is held fastened to the lower block 12 by the rivet 50, the base of the frame being depressed in its center portion to fit under the pivot plate and being bored to receive the shank of the rivet. The recess in the lower block is formed to receive the frame and consequently both the frame and the square pivot plate are firmly locked against movement in any direction by the rivet which conduces to economy of manufacture.

For throwing over the breaker bar when the push-through member is reciprocated, the spring 42 is mounted on a slide member 60 having its lower end forked to pivotally engage a cross-bar 61 formed centrally in the push-through member by cutting out portions thereof. The upper end of the slide member projects loosely through an opening in the top of the breaker bar. Being under partial compression the spring abutting at one end the top of the breaker bar and at its other end the shoulders of the forked portion of the slide holds it in pivotal engagement with the cross-bar 61 and since the push through member is always at one end or the other of its path of reciprocation, the lower ends of the slide member and the spring are in an off center relation to the breaker bar. The result is that when the push-through member is moved from one end of its path to the other end, the lower end of the slide member is moved also further compressing the spring and throwing the breaker bar in the opposite direction as soon as it passes the center thereof. In order that the upright ends of the frame 54 may serve as stops to limit the movement of the breaker bar in both directions, the base of the frame is centrally restricted in width (Fig. 7) to correspond to the width of the pivot plate so that the breaker bar may be of less width than the pivot plate member to engage its ends. When the breaker bar is thrown over, the free end of the slide member moves freely through the top of the bar to permit shortening of the spring in going over the center.

The fixture hereinbefore described is in practice enclosed in a shell 70 and cap 71 of well-known construction, the fixture being placed in the shell in assembled condition and as a unitary structure. This is generally done by first passing the conductors through the center hole in the cap and then securing them to their respective binding screws on the fixture after which it is pushed into the shell, the push buttons entering open longitudinal slots in the cap end of the shell. The shell is then locked into the cap. A shell 75 of paper or other insulating material is generally interposed between the metal shell 70 and the fixture to prevent short circuits.

The operation of my switch is as follows: Assuming the positive wire to be that designated 32, the current when the switch is closed flows from said wire through standard 14, contact butt 45, contact 41, breaker bar 40, pivot plate 49, rivet 50, central contact 51, lamp filament (not shown), lamp socket 26, screw 24, standard 16 and negative wire 34. To prevent short circuiting through the screw 20 and socket 26, the latter is cut away around the head of the former and a washer 76 of insulating material is interposed between the two. When the breaker bar is separated from the fixed contact the circuit is broken and the lamp goes out.

The opening and closing of the circuit by the switch is accomplished by pushing in that end of the push-through member which is outermost, the red push-button, if it is desired 35 to turn the light on or the black push-button for turning the light off. When the push-through member is thus operated, the spring slide is carried over the center compressing the spring and as soon as it passes over the 40 center of the breaker bar the latter is thrown by a rapid movement in a direction opposite to the movement of the push-through member. The contact thus made or broken with the fixed contact plate is rapidly effected. 45 The fixed contact is so adjusted that it hangs somewhat lower when the circuit is open so that the breaker bar in closing the circuit first strikes the turned up points of the contact and pushes it slightly upwardly as it 50 slides over to make the full contact. This insures an efficient sliding contact over a relatively large area. The end of the slide member 60 projecting through the top of the breaker bar is accommodated by the central recess of the contact. By providing a rapid sliding contact arcing is diminished.

It will be observed that my switch is extremely simple in construction and operation, embodies few parts and is very durable. 60 The push-through member and the frame in which it moves are of such form that there is no possibility of these parts becoming loose or inoperative after long use. The offset ends of the push-through member act as stops to limit its reciprocation in both directions.

Another advantage of my invention is that a switch constructed in accordance with the invention can be made at a low cost for parts and for assembling. The central rivet fastens the three parts in position, the frame, the pivot plate and central lamp contact and the parts of the switch may be put together rapidly without requiring manipulation of fastening means. The two insulating blocks and lamp socket are fastened in assembled 70 relation by four screws. It will be apparent that the assembling of lamp sockets as thus constructed is a simple matter which may be accomplished rapidly.

Although I have described my invention as exemplified in a switch for lamp sockets I do not desire to be restricted to that particular use since my invention may be utilized for switches generally or for other particular uses. Furthermore, it is to be understood that my invention is not to be limited to that form herein shown and described since it is obviously capable of embodiments in other forms of construction which would be apparent to one skilled in the art and within the 80 purview of the following claims.

What I claim is:

1. A switch having, in combination, a fixed contact, a U-shaped frame having its upwardly turned ends each provided with a right-angled recess opening out the top side thereof, a push-through member slidably mounted in said recesses and held against lateral movement by the sides thereof, said member having its ends offset to act as stops by engagement with the upwardly turned ends of said frame to limit the reciprocation of said member, the offset ends thereof being provided with push buttons, a movable contact and a spring actuated by said push-through member for throwing said movable contact into and out of engagement with said fixed contact.

2. A switch having, in combination, a fixed contact, a U-shaped frame having its turned ends each provided with a right-angled recess opening out the top side thereof, a push-through member in the form of a flat bar slidably mounted in and held against lateral movement by said recesses and having its two ends offset to limit the reciprocation of said member by engagement with the turned ends of said frame, a movable contact and a spring actuated by said push-through member for throwing said movable contact into and out of engagement with said fixed contact; said recesses each being slightly enlarged at the inner angle portion thereof to permit said push-through member to be mounted in and removed from said recesses.

3. A switch having, in combination, a fixed contact, a U-shaped frame having its upwardly turned ends each provided with a right angled recess opening out the top side thereof, a push-through member slidably

mounted in said recesses and held against lateral movement by the sides thereof, said member having its ends offset to act as stops by engagement with the upwardly turned ends of said frame to limit the reciprocation of said member, the offset ends thereof being provided with push buttons, a breaker bar pivotally mounted centrally said frame and straddling said member and a spring operated by said push through member for throwing said breaker bar into and out of engagement with said fixed contact to open and to close a circuit.

4. A switch having, in combination, a fixed contact, a U-shaped frame having its upwardly turned ends each provided with an L-shaped recess opening out the top side thereof, a push-through member slidably mounted in said recesses and held against lateral movement therein, said recesses being slightly enlarged at the angle portion thereof to permit said member to be mounted therein or removed therefrom by a slight turning movement, a movable contact and a spring actuated by said push-through member for throwing said movable contact into and out of engagement with said fixed contact.

In witness whereof, I have hereunto set my hand this twenty-third day of August, 1928.

FRANK E. JOHNSON.
